UNITED STATES PATENT OFFICE

2,195,832

GRIP CLAW HOLDER

Gustave Wagenhauser, New York, N. Y.

Application March 6, 1939, Serial No. 260,022

4 Claims. (Cl. 146—216)

This invention relates to gripping and holding claw devices for large pieces of meat, like corned beef, roast beef, ham, etc., and has for its main object to provide a device of this character which will be simple in construction and efficient in use.

Another object of this invention is to provide a device as characterized hereinbefore, which will protect the hand of the user from the touch and the heat of the piece of meat, or the like, gripped and handled with my device.

Still other objects of my invention will be apparent as the specification of the same proceeds, and, among others, I may mention: to provide a device of this type which will automatically grip the piece of meat or other object, so that no effort of the user will be necessary to so hold and secure the object in its grip, which will have automatic limiting means for its penetration into the object and which will aid in slicing a piece of meat, whether in cold or in a hot condition.

In the drawing forming a part of this specification and accompanying the same;

Fig. 1 is a side elevation of my device in a closed operative normal position, and

Fig. 2 is an end elevation thereof, the view being taken as indicated by an arrow 2 in Fig. 1;

Fig. 3 is another side elevation, from the opposite side to that of Fig. 1;

Fig. 4 is a similar side elevation to Fig. 3, but in an open position, just before applying my device, and on a reduced scale, and

Fig. 5 is a sectional detail, the section being taken on the line 5—5 of Fig. 3.

Referring now to the drawing more in detail, by characters of reference, my meat gripping and holding device is generally indicated by the numeral 10, and is composed of two main parts 11 and 12 which are generally similar to one another, aside from some details to be explained hereinafter, but they are oppositely placed and arranged, that is, symmetrically to a central vertical plane of my device.

Describing now part 11 more in detail, the same has a curved plate base portion 13, preferably being formed as a part of a hollow cylinder or tube and having considerable widths between its two side edges 13a and 13b, as shown in Fig. 2.

A perpendicular plate flange 14 is secured on the base curved plate 13, at its edge 13b, or said flange plate 14 may be formed integral with said base plate 13. The upper free edge of the flange plate 14 may be curved as indicated at 15 in an elliptical manner, but it will be understood that the same may take any other appropriate shape. The upper edge 15 continues to a substantial distance beyond the center line of my device as indicated at 15a, from which point a generally radial terminating edge or side 16 drops downwardly towards the center of the device and said

terminating edge shows a recessed curved portion 16a around said center, so as to avoid the hinge sleeve 17 provided at the inner end of the base plate 13.

The other main part 12 of my device is similarly constructed to the part 11, as has been mentioned hereinbefore, and it will show a base plate 18, a perpendicular flange plate 19 terminating in the inwardly dropping edge 20 which again has a recessed curved portion 20a to avoid the said sleeve 17, and the hinge sleeve 21 formed of the base plate 18. A hinge pin 22 is passed through the sleeves 17 and 21, thereby forming a pivoted connection between the base plates 13 and 18, as will be understood. Two inwardly curved spikes 23 are provided at the lower end of the base plate 13, and an inwardly curved single spike 24 may be secured towards the upper central part of the said base plate. The base plate 18, of part 12, shows two similar oppositely placed lower spikes 25, and an upper central spike 26.

At about the central upper portion of base plate 13, an upwardly and outwardly inclined handle 27 is secured into said plate, and a similar but oppositely inclined handle 28 is secured into the base plate 18. A comparatively strong, heavy spiral spring 29 is arranged between the two handles and will have the normal tendency of pressing them outwardly, thereby pressing the base plates 13 and 18, as well as their spikes, towards one another.

The flange plate 11 may be bent inwardly as at 30, and then continued in parallelism with its original portion, but inwardly spaced therefrom to its terminating edge or side 16 as indicated at 31. The purpose of such offsetting being to permit the inner end portion 32 of the other flange plate 19 to slide in overlapping relation on the outside of the offset portion 31, when the two parts are rocked around their pivot, as will be understood. A projection 33 is provided near the end of the outer edge of the flange plate 14, and an inwardly bent pin 34 is provided at the end of the upper edge of the flange plate 19, and in the normal closed position of my device, as illustrated in Figs. 1 and 3, the projection 33 and pin 34 will be pressed against each other through the action of the spring 29 and thereby provide a limit to the opening of the handles 27 and 28, and the closing of the base plates 13 and 18 with their spikes under the action of said spring.

To retain the spring 29 in its position in the device, the two ends thereof will encircle the projections 27a and 28a on the handles 27 and 28, respectively.

The use and operation of my device will be obvious from the description herein and by inspecting the drawing. My device normally is in the position shown in Figs. 1 and 3, and when it is desired to use the same, handles 27 and 28

will be gripped and pressed together by the hand of the user, against the action of the spring 29, which also will be compressed, and it will be obvious that the portion 32 of the plate 19 will ride 5 on the outside and along the portion 31 of the plate 14, the projection 33 and pin 34 being separated from one another, and the base plates 13 and 18 with the spikes also being opened, as indicated in Fig. 4. The device will be held in such 10 a position against the action of the spring and placed in a desirable manner over the piece of meat, or the like, as, for instance, over and around the portion of a large chunk of corned beef, roast beef, ham, and the like, and then the 15 pressure of the hand of the user on its handles 27 and 28 will be relaxed, permitting the spring 29 to again drive them further apart from one another, in opposite directions, and thereby forcing the base plates 13 and 18 nearer to each other 20 on their pivot 22, their spikes biting deeply into the meat, to be lifted or otherwise handled. The wide tubular base plates 13 and 18 will protect the hand of the user from getting into contact with the greasy and hot meat, which action will 25 also be aided by the protective or shield flange plates 14 and 19 which, of course, will ride upon one another in an opposite direction until their limit members 33 and 34 will again meet, as indicated in Figs. 1 and 3. The meat so gripped by 30 my device may then easily be lifted, moved and handled and even sliced without any effort in securing the grip thereon. In the slicing operation, the flange plates 14 and 19 will protect the fingers of the user, and will generally aid in 35 accurate slicing, as will be obvious.

It also will be understood that differently shaped and arranged various numbers of spikes may be used, instead of the six shown in the drawing, while my experience has been that 40 such an arrangement and such an elongated inwardly curved shape for said spikes, strong at the base, and gradually narrowing to a point, is the preferred one.

It will be seen that I provided a grip claw holder which may grasp and firmly hold any appropriate object without danger of letting it drop, and without any further effort by the user, the device automatically closing upon the object through the action of the spring therein, while 45 the handles, or even one of them, will permit the user to comfortably hold the device with the object therein in any desired position, or for any purpose.

It also will be obvious that my device provides protection for the hand of the user, preventing the burning or cutting thereof, as has been pointed out hereinbefore. The spring of my device can be made to exert any desired amount of pressure, and it may easily be exchanged or 50 replaced.

As also has been mentioned, my grip claw holder is particularly adapted to grasp hot roast or boiled meats of any kind, and the wide curved plates and the perpendicular flange plates will 55 provide the necessary protection for the hand and fingers of the user.

My device may be made of any appropriate material, like brass, copper, steel, or metal alloys, and it may be shaped and finished attractively 70 and hygienically, like by silver, chromium or nickel plating.

It also will be understood that while I have shown and described a preferred embodiment of my device, changes and variations may be resorted to in the constructional details, combinations and elements thereof, and I reserve my 5 rights to all such changes and variations which are within the spirit of this specification and the scope of the claims hereunto appended.

What I claim is new, is:

1. A grip claw holder, having two curved plates 10 pivoted to one another, spikes projecting from said curved plates inwardly opposing each other, a handle secured on the outside of each curved plate, and resilient means between said handles normally pressing them outwardly, and said spike 15 plates inwardly toward one another, a perpendicular plate flange on the edge of each curved plate, at the same side of the device.

2. A grip claw holder, comprising two curved plates pivoted to one another, spikes projecting 20 from said curved plates inwardly opposing each other, a handle secured on the outside of each curved plate, and resilient means between said handles normally pressing them outwardly, and said spike plates inwardly toward one another, 25 said resilient means being adapted to be counter-acted by exerting opposite pressures on said handles, a perpendicular plate flange on the edge of each curved plate, at the same side of the device, the portion of one said plate flanges adjacent to the other one being bent and offset 30 inwardly, to permit an overlapping movement of one plate flange over the other when said resilient means is counter-acted, and said curved plates pivotally opened.

3. A grip claw holder, comprising two curved plates pivoted to one another, spikes projecting from said curved plates inwardly opposing each other, a handle secured on the outside of each curved plate, and resilient means between said 40 handles normally pressing them outwardly, and said spike plates inwardly toward one another, said resilient means being adapted to be counter-acted by exerting opposite pressures on said handles, a perpendicular plate flange on the edge of 45 each curved plate, at the same side of the device, the portion of one of said plate flanges adjacent to the other one being bent and offset inwardly, to permit an overlapping movement of one plate flange over the other one, when said 50 resilient means is counteracted, and said curved plates pivotally opened, and co-operating limiting means on said plate flanges, to limit the outward movement of said plate flanges with relation to one another under the action of said resilient means.

4. A grip claw holder, having two curved plates pivoted to one another, spikes projecting from said curved plates inwardly, opposing each other, a handle secured on the outside of each 60 curved plate, and resilient means between said handles normally pressing them outwardly, and said spike plates inwardly, toward one another, a perpendicular plate flange on the edge of each curved plate, at the same side of the device, said 65 plate flanges being in closely adjacent planes of side by side relation and being adapted to partly overlap each other when said curved plates are in an open position.
